A. R. BROWN.
MOLD FOR MAKING ACUPUNCTURE INSTRUMENTS
No. 82,686. Patented Oct. 6, 1868.

United States Patent Office.

ANSON R. BROWN M. D., OF ALBION, MICHIGAN.

Letters Patent No. 82,686, dated October 6, 1868.

IMPROVEMENT IN MOULDS FOR MAKING ACUPUNCTURE-INSTRUMENTS.

The Schedule referred to in these Letters Patent and making part of the same.

TO ALL WHOM IT MAY CONCERN:

Be it known that I, ANSON R. BROWN, M. D., of Albion, in the county of Calhoun, and State of Michigan, have invented a new "Setting-Mould" for the Construction of the Puncturing Plunger-Heads in "Acupuncture-Instruments," and I do hereby declare that the following is a full, clear, and exact description of the same, reference being had to the annexed drawings, forming a part of this specification, in which—

Figure 1 is an elevation in section of the setting-mould and enclosed plunger-head, as cast therein.

Figure 2 is a plan view of the former, composing a part of the mould.

Figure 3 represents the plunger-head and stem, armed with the acupuncturing-lancets, and detached from the mould.

Similar letters of reference indicate like parts in all the figures.

The necessity for a special mould in which to cast the plungers of acupuncture-instruments, and to set the puncturing-lancets within such casting, arises from the great difficulty and expense of adjusting them by any ordinary mechanical manipulation, for the lancets are arranged in pairs, and converge together until they just touch each other, after the fashion of the blades of a drawing-pen, so as to deposit the irritating-fluid in the punctures, in a manner somewhat analogous to that in which the ink is deposited by the said pen on the paper.

The object of my invention is to dispense with all hand-skill in the setting and adjusting the lancets in the plunger-heads themselves, and to set them up and adjust them within a mould, in permanent sockets, and in a ready and undeviating manner, so that when the melted metal is poured into the mould to form the plunger and stem, it will flow around the butt-ends of the lancets, and when the plunger is removed, the lancets will be perfectly adjusted, ready for use, and set firmly in the metal.

The manner in which I construct the former-disk, represented at F, and constituting the most important part of the mould, (Figure 1,) is to erect a turned mandrel, provided with two thin disk-plates, at a proper distance apart, the upper plate being perforated with slots, as seen in Figure 2, to receive the body of the lancets, and the lower plate having slight indentations, to receive the two converging points in one depression.

A casing is then formed around the plates, and soft metal is poured in around the lancets, which, in this case, merely act as cores to form the mortises in said former, in which mortises the blades of similar lancets are inserted, to cast the metal around their projecting butt-ends, as aforesaid, in the construction of the plunger and stem, indicated respectively by the letters E and B.

I generally construct the mould for the plungers of metal, and bore out the cavities, both for the reception of the casting, and also for the insertion of the "former," in which the lancets are placed, in the mortises, cast as heretofore explained.

C is a vent-wire, and D is a wire core, for casting a hole in the plunger, to receive a spring, for throwing said plunger back after the lancets have acted.

It will be seen that the former, F, is furnished at the bottom with a soft-metal plate, indicated at G. This plate is designed to support or gauge the points of the lancets, shown by the figures 1, 2, 3, 4, &c., so that they will lie on a true plane when placed in the mortises, with their butt-ends projecting upwards into the mould, as in fig. 1.

Soft metal is poured in at the sprue-holes to fill the mould, and, when cold, the casting and former are withdrawn, and the lancets are sprung out of the angular mortises in the former, leaving the cast plunger with the lancets truly cast in it, as seen in Figure 3.

What I claim as my invention, and desire to secure by Letters Patent, is this:

I claim the former, F, having slits or mortises cast through it, as described, to receive the blades of puncturing-lancets, 1, 2, 3, &c., in combination with a mould for casting the plungers E B, substantially as and for the purpose specified.

A. R. BROWN, M. D.
